UNITED STATES PATENT OFFICE.

FLETCHER E. FELTS, OF LOS ANGELES, CALIFORNIA.

SWITCHING SYSTEM FOR SUSPENDED RAILWAYS.

Application filed July 1, 1927. Serial No. 202,851.

This invention relates to a switching system for suspended railways of the type disclosed in U. S. Patent #928,435, granted to me July 20, 1909, and the object of the invention is to provide a simple and efficient means by which suspended cars or trains may be transferred from a main line of track onto another main line and by which the operation of the switch mechanism may be automatically controlled.

The invention consists of suspended sections of straight track and curved track disjoined from continuous straight trackway and curved trackway respectively, and of means for moving such suspended sections of track into alignment with either the straight trackway or the curved trackway.

The accompanying drawings illustrate a preferred embodiment of the invention, and 20 therein,

Fig. 1 is a plan view showing diagrammatically an electrically controlled mechanism for moving disjoined sections of curved and straight track into alignment with curved and 25 straight trackway respectively.

Fig. 2 is a side view showing the straight and curved sections of track and the carriers therefor.

Fig. 3 is a fragmentary detail showing 30 means carried by a car for controlling the electrical mechanism.

Fig. 4 is a plan view showing the disjoined sections of curved track in alignment with the curved trackway and the disjoined section of straight track out of alignment with the straight trackway.

Fig. 5 is a plan view showing means for rotating a disjoined section of track to align same with a curved or straight track of intersecting trackway.

Fig. 6 is a fragmentary end view showing the carriage mount and the rack carried by the carriage for operating the disjoined section of crossing tracks or rails.

Fig. 7 is a fragmentary view showing a disjoined section of track and the rotatable support therefor.

Fig. 8 is a diagrammatic view of electrical mechanism for controlling the movement of 50 the disjoined tracks in one direction and

Fig. 9 is a diagrammatic view of electrical mechanism for controlling the movement of the disjoined tracks in another direction.

Referring in detail to the form of embodiment of the invention shown in the drawings, 55 1 and 2 indicate parallel straight tracks or

rails for cars traveling respectively in opposite directions, and 3 and 4 indicate tracks or rails curving away from said straight tracks 1 and 2. The respective straight tracks 1 and 2 and the respective curving tracks 3 and 4 are arranged to be suspended from a suitable structure generally shown at 5, in Fig. 4. The curved tracks 3 and 4 terminate at the point of divergence thereof from the main 65 tracks 1 and 2 and at that point are separated therefrom. The continuity of the parallel straight tracks or rails 1 and 2 is interrupted by gaps A and B, respectively, Fig. 4. The continuity of the curved tracks 3 and 4 is arranged to be established by track sections 3' and 4' respectively, and the continuity of the straight tracks 1 and 2 is arranged to be completed by sections 1' and 2', the respective 70 sections 3' and 4' and 1' and 2', being arranged to be moved into alignment with the respective tracks by means hereinafter described.

The continuity of the curved track 4 and the continuity of the straight track 1, at the 80 point of intersection of such tracks 4 and 1, is interrupted by gaps C and D respectively, as shown in Fig. 5, and the continuity of said tracks 4 and 1 at the point of intersection thereof is arranged to be established by a 85 track section 6, rotatable as hereinafter described to align the same with the curved track 4 or with the straight track 1, and concurrently with the movement of the track sections 4' and 2'.

The sections of tracks 1' and 3' are suspended by hangers 7 and 8, respectively, from a carriage 9, supported by pairs of flanged wheels 10 and 10' which are arranged to ride upon tracks 11, disposed at right 95 angles to the tracks 1 and 2 and 3 and 4 which are suspended from a suitable structural support indicated at 11'.

The pairs of wheels 10 and 10' are secured to axles 12 and 12', which are journaled in 100 the carriage 9. Upon the axle 12 is mounted a sprocket 13, which through the medium of a chain 14 is connected with a sprocket 15, secured to the shaft of an electric motor 16, through which the rotation of said axle 12 105 and the movement of the carriage 9 along the tracks 11 is effected. The rotatory motion of the axle 12 is communicated to the axle 12', through a chain 17, running over sprockets 18 and 18' respectively.

The sections of tracks 2' and 4' are suspended by hangers 19 and 20, from a carriage

21, supported by pairs of flanged wheels 22 and 22' which are arranged to ride upon the tracks 11. The pairs of flanged wheels 22 and 22' are secured to axles 23 and 23' which are journaled in the carriage 21. Upon the axle 23 is mounted a sprocket 24, which through the medium of a chain 25 is connected with a sprocket 26, secured to the shaft of an electric motor 27, through which the rotation of said axle 23 and the movement of the carriage 21, along the tracks 11 is effected. The rotatory motion of the axle 23 is communicated to the axle 23', through a chain 26', running over sprockets 27' and 27" secured 15 to said axles 23 and 23'.

The section 6 of track that is arranged to complete either the straight track 1 or the curved track 4 is, as stated, arranged to be operated concurrently with the movement of the sections of track 2' and 4' and to accomplish the rotation of said section 6 to aline the same with either of the tracks 1 and 4, by the rectilinear movement of the carriage 21, I have provided the arrangement shown more particularly in Figs. 4, 5 and 7, and comprising the following structure. Onto the side of the carriage 21 is secured a rack 28, with which meshes a pinion 29, pinned or otherwise secured to one end of a shaft 30 journaled near one end thereof in a suitable support 31 and near the other end thereof journaled in a suitable support 32, that is carried by a tie structure 33 which is connected to the rail supporting structure 5. On the other 30 end of the shaft 30 is secured a bevel gear 34, which meshes with a similar bevel gear 35 on one end of a shaft 36, which extends at right angles to said shaft 30, and which is journaled in suitable supports 37 and 37' attached to said tie structure 33. On the end of said shaft 36 is fastened a bevel gear 38, which meshes with a horizontal bevel gear 39. The bevel gear 39 fits over preferably a squared extension 40 rising centrally of and 45 vertically from a turntable 41 which is rotatable upon a support 42, that is fastened to said tie structure 33, suitable roller bearings 43 and 44 being provided to reduce friction incident on the rotation of said turntable. The section 6 of track is suspended from said turntable by hangers 45, and as seen in Fig. 5 is substantially straight. It will be seen from this description that the movement of the carriage 21 in either direction, transfers its movement through the media detailed, to the turntable 41, which will aline the section 6 of track carried by it with either the curved track 4 or the straight track 1.

Both carriages 9 and 21 are independently 60 movable on the track 11 by the respective motors 16 and 27. The electrical power circuits for the motors of both carriages 9 and 21 being identical, one only will be described in detail, similar reference characters denoting 65 similar parts. It will be observed that the

main line or the straight tracks 1 and 2 are arranged to be normally open, and that the curved or diverging tracks 3 and 4 are arranged to be normally closed. The system to be described therefore is controllable by a 70 car that is to take the switch or diverging track to cause the diverging track section to be moved into alinement with and to open the curved track, while at the same time the straight section of track is caused to be 75 moved out of alinement with and close the main or straight track; the system is also controllable by the car that has passed onto the diverging track to cause the main or straight track to be opened by the movement of the 80 straight track section into alinement with the straight track while at the same time moving the diverging track section out of alinement with and closing the curving or diverging track. 85

Referring to Fig. 3, mechanism is illustrated which is arranged to be carried by a car E, and which is arranged to initiate the flow of electrical current through a plurality of circuits, presently described, whereby the 90 switching system is set in operation. This mechanism comprises a pair of arms 47 and 47', pivotally connected intermediate the ends thereof to the car. Between the forward ends of the respective arms is disposed an electro-magnet 48, which is in an electrical circuit 49, that also includes a source of electrical energy, as a generator 50, and a switch 51, arranged to be operated by the operator of the car. The rear ends of the 95 respective arms 47 and 47', are normally held drawn toward each other by a spring 51', which also causes the front ends of said arms to be held away from both ends of the electro-magnet 48. When the electro-magnet is 100 energized by the closing of the switch 51, the front ends of the respective arms 47 and 47', will be attracted to and held on the respective poles of the electro-magnet 48. By this movement, the rear ends of said arms 47 and 105 47' are moved outwardly and into the path of contacts 52 and 52', and 53 and 53' by which a circuit, hereinafter described, is established whereby to energize one of the 110 motors carried by one of the carriages 9 or 115 21, and thereby cause the travel of said carriages in one or the other direction respectively.

Referring to Fig. 9,

The electrical system by which the movement of the carriages is effected in one or the other direction is shown as comprising the motor 16, a pole changer 54, an armature 55 to which said pole changer is connected at one end and which is movable about a central pivot 57; a pair of electro-magnets 56 and 56' for operating said armature about its pivot and thereby control the movement of the pole changer. The armature is held normally away from said electro-magnets by 120 125 130

springs 58 and 58'. Each of the electro-magnets is provided with a supplemental winding 59 and 59' terminating in a contact point 60 and 60' which is arranged for alternate engagement by said armature 55. The contacts 52 and 52' are in an electrical circuit 61, which is a branch of a power line 62, and which includes one of the electro-magnets, namely 56. Assuming that the arms 47 and 47' carried by a car have engaged the contacts 52 and 52', a circuit is completed which energizes the electro-magnet 56. One end of the armature 55 will thereby be drawn to the pole of the electro-magnet 56, and by this movement of said armature 55 the pole changer will be operated to establish the direction of flow of the current to the field magnets of the motor. At the same time that the armature 55 is attracted to the pole of the electro-magnet 56, the armature contacts with the contact point 60 in which the winding 59 terminates, thereby completing a circuit which includes the armature of the motor, the winding 59 of the electro-magnet 56, the contact point 60 and the armature 55, which is grounded. When the motor is thus set in operation, the carriage will be moved and the track section 1' alined with the straight track 1. The supplemental windings 59 and 59' are provided on the electro-magnets 56 and 56' respectively, in order to hold the electro-magnets 56 and 56' energized after the initial circuit which includes the contacts 52 and 52', and 53 and 53', has been interrupted by the passing of the contact arms 47 and 47'. When the carriage has been moved the distance required to bring about the alinement of the particular track section 3' with the respective track 3, the power circuit is broken by the disconnection of the armature 55 with the electro-magnet 56, which is effected through the medium of a deflector 63 which is disposed in the path of travel of the end of armature 55. Stop members 64 and 64' and 65 and 65' respectively are provided on the cross rail 11 on which the carriages 9 and 21 travel, to prevent the travel of said carriages and the movement of the rail sections 1' and 3' and 2' and 4' beyond the point of alinement with the respective tracks 1 and 3 and 2 and 4. These stop members 64 and 64' and 65 and 65' are shown in Fig. 4. After the car has passed over the curve onto the straight track, the section 1' of track is arranged to be moved into alinement with the straight track 1. This is accomplished by the arms 47 and 47' making contact with the contacts 53 and 53'. In so doing, a circuit is completed and the electro-magnet 56' is energized. Thereby the other end of the armature 55 will be drawn to the pole of the electro-magnet, as shown in Fig. 8, and by this movement of the armature 55, the pole changer 54 will be operated to reverse the flow of the current to the field mag-

nets of the motor. At the same time that the armature 55 is attracted to the pole of the electro-magnet 56', the armature contacts with the contact point 60' in which the winding 59' terminates, thereby completing a circuit which includes the armature of the motor, the winding 59' of the electro-magnet 56', the contact point 60' and the armature 55, which is grounded. When the motor is thus set in operation, the carriage will be moved and the track section 1' alined with the straight track 1.

What I claim is:

1. A switching system for suspended railways comprising suspended straight tracks for cars traveling in opposite directions and curved tracks diverging from the straight tracks for cars traveling in opposite directions, each of the respective straight tracks and curved tracks at substantially the points of divergence of the curved track from the straight tracks having a section disjoined therefrom, a plurality of carriers, each supporting a disjoined section of straight and curved track and means to move said carriers independently of each other to aline the sections carried thereby with the respective straight or curved tracks. 80
2. A switching system for suspended railways comprising suspended straight tracks for cars traveling in opposite directions and suspended curved tracks for cars traveling in opposite directions, said curved tracks diverging from said straight tracks, and each of the respective straight tracks and curved tracks at substantially the points of divergence of the curved tracks from the straight tracks having a disjoined section, means for suspending said disjoined sections, and means controllable by cars traveling on said tracks to operate said suspending means and thereby aline the sections carried thereby with the respective straight or curved tracks. 95
3. A switching system for suspended railways including suspended straight tracks and curved tracks diverging from said straight tracks and sections of tracks disjoined from said straight and curved tracks, a plurality of carriers each having supports for two track sections, and a motor to operate each carrier independently of the other thereby to cause said disjoined sections of track to be moved into and out of alinement with said straight and curved tracks. 110
4. A switching system for suspended railways including straight tracks and tracks curving away from said straight tracks, and sections of track disjoined from said straight and curved tracks, a plurality of carriers, each having a support for two track sections, a trackway supporting said carriers, motors to move said carriers independently of each other along said trackway, and means operable by cars traveling on said straight and curved tracks to control the 125

motors and the movement of said carriers to aline one of the disjoined sections with the respective track and simultaneously remove the other of said sections from alinement 5 with its respective track.

5. A switching system for suspended railways comprising straight tracks and curved tracks diverging from said straight tracks, each of said straight tracks and curved 10 tracks having a section disjoined therefrom, a plurality of carriers, each supporting two track sections, means operable by cars traveling in one direction to move said carriers in one direction and thereby cause one of the 15 disjoined sections to aline with its respective track, and the other disjoined section to be moved out of alinement with its respective track, and means operable by said cars to move said carriers in the opposite direction 20 thereby to cause the alined disjoined section to be moved out of alinement with its respective track and the other section to aline with its respective track.

6. A switching system for suspended rail- 25 ways comprising straight tracks and curving tracks diverging from said straight tracks, one of said curving tracks also intersecting one of said straight tracks, sections of tracks disjoined from said straight and curving 30 tracks at substantially the point of divergence of said curving tracks from said straight tracks, a single section of track disjoined from one of the straight tracks and one of the curving tracks at the point of intersection thereof, carriers each supporting two track sections, means to move said carriers independently of each other to aline either of the sections carried thereby with its respective track, a support for said single 35 section of track, and means to move said single section of track into or out of alinement with either the straight or curved track.

7. A switching system for suspended railways comprising straight tracks, and curving 45 tracks diverging from said straight tracks, the ends of one of the straight tracks and one of the curving tracks at the point of intersection thereof being spaced relatively to each other, sections of track disjoined from 50 said straight track and curving tracks at substantially the point of divergence of the curving tracks from the straight tracks, a single

section of track disposed in the space between the ends of the straight track and curving track and arranged to complete or interrupt the continuity of said straight or curving tracks, carriers each having supports for two track sections, means to operate said carriers independently of each other to cause the sections carried thereby to aline with their respective tracks, a support for said single sections of track, and means operable by the movement of one of said carriers to move said single section into or out of alinement with either the straight or curving track. 65

8. A switching system for suspended railways comprising in combination with straight tracks and tracks diverging from said straight tracks, sections disjoined from said straight and divergent tracks respectively, supports for said sections, and means to move said supports independently of each other to cause the sections carried thereby to aline with the respective straight or divergent tracks. 75

9. A switching system for suspended railways comprising straight tracks and curved tracks diverging from said straight tracks and one of said curved tracks and one of said straight tracks terminating at substantially 80 the point of intersection thereof, sections of straight and curved track disjoined from said straight and curved tracks, means to move said sections of track into and out of alinement with the corresponding straight or 85 curved tracks, a single section of track for completing the continuity of the straight or curved track at the intersection thereof, and means to rotate said single section to aline same with either the straight or curved track. 90

10. A switching system for suspended railways, comprising straight tracks and curved tracks diverging from said straight tracks, sections of straight and curved track disjoined from said straight and curved tracks, 95 respectively, supports for said sections, a motor to move each said support, and means controllable by the cars traveling on said tracks to operate said motors independently of each other and thereby cause the sections 100 carried by said supports to aline with either the straight or curved tracks.

In testimony whereof I have set my hand.

FLETCHER E. FELTS.
